CHAIN GRATE FOR FURNACES

Filed Jan. 26, 1927

Inventor,
Alfred W. Dennis,
by Herbert H. Dennis, Attorney.

UNITED STATES PATENT OFFICE.

ALFRED WILLIAM BENNIS, OF LITTLE HULTON, BOLTON, ENGLAND.

CHAIN GRATE FOR FURNACES.

Application filed January 26, 1927, Serial No. 163,758, and in Great Britain January 21, 1928.

This invention relates to improvements in moving chain grates for steam generator and other furnaces and has particular reference to that type of grate in which a plurality of links or grate bars are arranged on pivotal rods so as to form an endless chain for carrying the fuel through a furnace, my general object being to provide a chain grate in which a greater percentage of air space 5 is available to the grate, having finely-distributed effective air spaces, than is common with chain grates heretofore in use, can be utilized for combustion; such air spaces being arranged to provide for the efficient and satisfactory 10 burning of low grade fuels, including fuels low in volatile matter such as coke breeze, coke ballast, anthracite and anthracite fuels. My principal object is to provide air spaces in the grate bars or links so arranged that a 15 portion of the air required for combustion may be projected towards the incoming fuel to assist the lighting up of the fire bed, or alternatively, if desired, a portion of the air may be projected rearwardly of the furnace 20 depending upon the manner in which such links or grate bars are arranged on their pivotal rods.

This invention consists in the novel construction and combination of the parts hereinafter fully described and claimed.

In the drawings,

Fig. 1 is a side elevation of a portion of a chain grate showing one form of links composing the grate in accordance with the present invention.

Fig. 2 is a part plan and part section of a fragment of the grate.

Fig. 3 is a transverse section of two of the links on line 3—3 of Fig. 1.

Fig. 4 is a side elevation of a single link of those shown in Fig. 1.

The present invention consists in providing the links or bars *a* with inclined air channels *b* arranged on the side of the links. 45 These channels are inclined forwardly towards the front of the grate, the grate travelling in the direction of the arrow indicated in Fig. 1. These air channels are inclined at a slight angle to the longitudinal axis of the link, the channels being such that the angle of inclination is at a lesser angle than the normal angle of repose of the fuel to be burnt on the grate. On each link one inclined air channel *b* is situated directly 50 above and around one pivotal centre *c* of the link as considered when the grate is mov-

ing along the upper stretch whilst another inclined air channel *b'* forms with the next succeeding link in the rear, a similar shaped air channel. The air channels are so disposed that the riddlings or ash material falling into the grate may be readily discharged either at the front or rear drum *d*, sprocket or the like or both.

Each inclined channel *b* is provided with a continuation *e* partly concentric or thereabouts to the respective pivotal centres *c* whilst each channel *b'* similarly is provided with a continuation *e'*. The air channels *b* *b'* and their continuations *e* *e'* respectively 60 preferably increase in width from the points of air discharge *f* to the points *g* at which air enters them, or giving a jet effect on discharge and a wider lower portion admitting 65 or riddling or ash discharging readily at the points previously referred to.

No inclined air channel is employed intermediate of the two pivotal centres *c* of the link as in the case of a prior construction 70 of mine.

In addition to the inclined air channels *b* previously described I may employ at the upper adjacent sides of the links comparatively narrow air spaces *g*¹ for the supply 75 of additional air for combustion, such spaces being formed by reducing the width of the link at one or both sides at *h* to less than that at the hub portions *i*.

In accordance with a further feature of my invention the surfaces of the link *a* at 80 the sides of such narrow air spaces *g*¹ may be provided with a plurality of comparatively small grooves *j* to facilitate the passage of air. These grooves may be inclined 85 preferably in a direction similar to the angle or direction of the neighbouring inclined air channels *b* at the side of the grate bars or links.

In the preferred construction the two inclined air ports *b* of the link or grate bar *a* 90 are situated on one side only as shown in the drawing so that the opposite side *a*¹ of the link may be substantially flat.

What I claim is:

1. A chain grate including a number of 105 pivots arranged parallel to each other, a series of grate links mounted on said pivots, hub portions on said links, a tapering air inlet channel on the side of each of said links which extends around the rear side of the hub portion from the bottom to the top 110 thereof and thence upwardly and forwardly

to the tops of the links in a direction towards the incoming fuel on the grate, a second channel being formed and shaped similar to the first channel by the co-operation of each link with its next succeeding link in the rear thereof.

2. A chain grate including a number of pivots arranged parallel to each other, a series of grate links mounted on said pivots, hub portions on said links which are wider than the remaining portions of said links to provide longitudinal air passages between the sides of the upper portions of laterally adjacent links, a tapering air inlet channel 10 on the side of each of said links which extends around the rear side of the hub portion from the bottom to the top thereof and thence upwardly and forwardly to the tops of the links in a direction towards the incoming fuel on the grate and a second air channel similarly inclined towards the incoming fuel on the grate, the second channel being formed and shaped similarly to the first channel by the co-operation of each link with its next succeeding link in the rear thereof.

3. A chain grate including a number of pivots arranged parallel to each other, a series of grate links mounted on said pivots, hub portions on said links which are wider than the remaining portion of said links to provide longitudinal air passages between the sides of the upper portions of laterally adjacent links, upwardly and forwardly inclined grooves formed on the sides of said upper portions of the links, a tapering air inlet channel on the side of each of said links which extend around the rear side of the hub portion from the bottom to the top thereof and thence upwardly and forwardly 30 to the tops of the links in a direction towards the incoming fuel on the grate and a second air channel similarly inclined towards the incoming fuel on the grate, the second channel being formed and shaped similar to the first channel by the co-operation of each link with its next succeeding link in the rear thereof.

In testimony whereof I have hereunto set my hand.

ALFRED WILLIAM BENNIS.
